UNITED STATES PATENT OFFICE.

FRANÇOIS RICHARD, OF CLEVELAND, OHIO, ASSIGNOR TO THE RICHARD AUTO MFG. COMPANY, OF CLEVELAND, OHIO.

HINGE CONSTRUCTION.

1,325,109.

Specification of Letters Patent. **Patented Dec. 16, 1919.**

Application filed March 10, 1917, Serial No. 154,036. Renewed October 27, 1919. Serial No. 333,683.

To all whom it may concern:

Be it known that I, FRANÇOIS RICHARD, a citizen of the Republic of France, residing at 7800 Finney avenue, Cleveland, in the 5 county of Cuyahoga and State of Ohio, have invented a new and useful Improvement in Hinge Constructions, of which the following is a specification, the principle of the invention being herein explained and 10 the best mode in which I have contemplated applying that principle, so as to distinguish it from other inventions.

This invention pertains to hinge constructions and more particularly to the 15 combination with a curved casing and door of a concealed type of hinge. In the exemplification as disclosed by the drawings my invention is shown adapted to a curved automobile body.

20 My object has been to accomplish that which, so far as I have been able to learn, has been heretofore thought impossible by artisans of the trade. Upon inquiry of long established manufacturers I was informed 25 that a concealed type of hinge applied to a curved door and casing would not enable the former to be swung open through an arc of ninety degrees. If such has been an unsolved problem, my invention terminates its 30 perplexity.

With the foregoing and other objects in view the invention consists of the novel construction, combination and arrangement of parts as hereinafter more specifically described and illustrated in the accompanying drawings, wherein is shown an embodiment of the invention, but it is to be understood 35 that changes, variations and modifications can be resorted to which come within the 40 scope of the claims hereunto appended.

Adverting to the drawing:—

Figure I is a side elevation of an automobile embodying doors supported by my invention.

45 Fig. II is an enlarged broken view taken on line II—II of Fig. I with the door open and looking forwardly.

Fig. III is an enlarged inside view of portions of the body and door connected by my 50 hinge, showing the positions assumed by the parts when the door is closed.

Fig. IV is an enlarged plan section taken above the upper of the two hinges and with the door shut.

Fig. V is a similar view showing the door 55 swinging open.

I have instanced one particular use to which my present invention is well adapted by illustrating it in a form suitable to the type of automobile body now in favor. A 60 side elevation of such an automobile body appears in Fig. I and has been designated by the numeral 1. The body 1 is formed on each side with a pair of upright casing edges 2 to which doors 3 are to be hinged. 65 It should be understood that, as here exemplified, my invention is peculiarly useful as applied to what are known in the art as concealed hinges. A hinge of this character is adapted for accommodation in the hollow 70 interior of either the casing or the door, or both, so as to be hidden from view when the doors are closed. Of late years concealed hinges have come into considerable 75 vogue in the automobile industry and more recently automobile bodies have their outside surfaces curved over the areas where it was desirable to have one or more doors. This necessitated what are known as curved doors in order neatly to conform to the streamline 80 contour of the body as a whole. It is to be remembered that doors should ordinarily open through an angle of at least ninety degrees, and in the case of automobile doors it is preferable to so limit the swing of the door 85 and also preclude contact with the body. I believe I am the first to mount a curved door on a complementarily curved casing by means of a concealed hinge so that sufficient clearance will be afforded and at the same 90 time a neat edge fit insured.

The automobile body is fashioned with a convex outer surface 4 and interiorly adjacent the casing edges 2 with a reinforcing member 5. The side of the body structure, 95 as a whole, which is to face the interior of the automobile has no direct bearing upon my invention and no consideration will be given to it other than to draw attention to the dotted line in Fig. IV which may be assumed as defining it. While in actual use a pair of hinges would ordinarily be employed and the drawings so disclose, the description hereinafter will be confined to only one and accordingly the singular number 100 used. A hinge plate 6 of any approved shape, here approximately U shaped, is firmly set in near the casing edge 2 and may

be held in place and reinforced by an upright bar of steel 7 which appears in Figs. III and IV. In turn, integrally carried by or separately secured to the hinge plate 6 is a socket 8 having its axis substantially upright. Firmly fixed to the casing edges 2, so as to project beyond the same in a direction toward the door, is an upright angle iron 9 which is to serve the purpose of a stop 10 to limit the swing of the door toward its open position, as will hereinafter appear.

A hinge arm 10, which is bent almost to the form of a complete loop, is pivoted on a pin 11 which is seated in the socket 8. Heretofore marketed hinge arms have been bent very similarly like the configuration of my hinge arm 10 with one notable exception. Till now, so far as I am aware, the hinge arm, when the door is in its closed position, has always first extended directly inwardly from its pivot and thereafter in the general direction of the door which was to be carried thereby. According to my conception the hinge arm 10 first extends for a given distance at 12, when the door is closed, in a direction directly away from the door. Next it extends at 13 at nearly right angles and inwardly, then again at 14 in a direction substantially parallel to the portion 12 and in the general direction of the door, and finally, at a point beyond the position of the stop 9, is again bent at 15 at a substantially right angle and parallel to the portion 13. Finally, it is still again bent at 16, which portion is about in line with the portion 12. It is to the portions 15 and 16 that the door 3 is to be secured. Such door 3 includes in its structure a complementarily curved outside convex surface 17, an upright door frame angle 18 to which the portion 15 may be riveted or otherwise firmly fixed and which when the door is closed is in juxtaposition to the stop 9. Interiorly the door 3 is provided, along that one of its edges which is opposed to the casing edge 2, with a stiffening extension 19 of the angle 18 fastened with a slightly curved edge 20 as is clearly shown in Fig. IV. A straight line distance between the axis of the socket 8 and the plane of the edge casing 2 must be selected to exceed the straight line distance from the axis of the socket 8 outwardly to the farthest removed portion of the surface 4. The straight line

distance between the socket 8 and the innermost point on the toe of the angle 9 must 55 not exceed the distance from the axis of the socket 8 to that side of the portion 14 which is nearest the socket.

Artisans familiar with the hinge joining trade will readily understand the fact that 60 more clearance, during the swinging action of a door, is required when such door and the casing which mounts it are both alike curved outwardly. It will be manifest also that the arrangement, according to which 65 the hinge arm 10 first extends at 12 in a direction away from the door 3, serves at once to compel the door to be swung through a wider arc sufficient to cause its near edge 70 freely to move past the casing edge. The manner in which the stop 9 limits the swing of the door, by reason of the engagement of the portion 13 of the arm therewith, is indicated in dotted lines in Fig. V.

I claim:

1. A hinge construction adapted to be used with a casing and a door comprising a stiffening angle iron secured to said casing, another angle iron secured to said door and adapted to inclose the casing iron, said door 80 iron having a surface disposed at an angle to the inner side thereof, a pivot secured to said casing, and a hinge arm movable upon said pivot and secured both to the stiffening member and to the inner side of said door, 85 said arm extending a given distance from said pivot in a direction away from said door when the latter is closed whereby to afford the necessary clearance in opening the same.

2. A hinge construction adapted to be used with a hollow casing and a door having a pair of angularly related inner surfaces, comprising a pivot mounted within said casing, and a widely looped hinge arm 95 connecting said door and pivot, said pivot being spaced a lesser distance from the near edge of the door than the distance of an interjacent part of said loop from such edge, said hinge arm having angularly related 100 surfaces conforming and secured to said pair of door surfaces.

Signed by me, this 28th day of February, 1917.

FRANÇOIS RICHARD.
